CLAIM

(21) Appl. No.: **29/178,750**

The ornamental design for a double hung new construction J-channel frame sill for a window, as shown and described.

(22) Filed: **Mar. 31, 2003**

DESCRIPTION

(51) LOC (7) Cl. **25-01**

The FIGURE is a front perspective view of a double hung new construction J-channel frame sill for a window, showing our new design, the rear perspective view being a mirror image, and which is shown fragmented indicating indefinite length.
